UNITED STATES PATENT OFFICE.

DELPHIS BEAUPRE, OF KANKAKEE, ILLINOIS.

IRONING-BOARD, WORK-BENCH, OR THE LIKE.

1,314,940.

Specification of Letters Patent.

Patented Sept. 2, 1919.

Continuation in part of application Serial No. 169,262, filed May 17, 1917. This application filed November 18, 1918. Serial No. 262,998.

To all whom it may concern:

Be it known that I, DELPHIS BEAUPRE, a citizen of the United States, residing at Kankakee, in the county of Kankakee and 5 State of Illinois, have invented certain new and useful Improvements in Ironing-Boards, Work-Benches, or the like, of which the following is a specification.

This invention has for its object the provision of a novel supporting means for ironing boards, work benches, or similar devices involving means in combination with such a board for attaching the latter to a main or sustaining object, including an operable supporting member for controlling the attaching means, and means coöperating with the operable supporting member to prevent accidental movement thereof.

A further object in view is to provide for 10 adjustment of the board at different heights by a novel extension arrangement in the supporting leg and its brace member, such that the movement of extension element of the leg effects a corresponding or requisite 15 movement of the extension element of the brace.

With the above and other objects in view this invention consists in the construction, 20 combinations, and arrangement of parts, all 25 as hereinafter more fully described, claimed, and illustrated in the accompanying drawings, wherein:

Figure 1 is a side elevation of a device constructed in accordance with this invention in extended operative position.

Fig. 2 is an end view thereof, looking at the brace side;

Fig. 3 is a view of the device in collapsed or folded position;

Fig. 4 is a bottom plan of the invention folded as in Fig. 3;

Fig. 5 is a vertical sectional view on the line 5—5 of Fig. 1;

Fig. 6 is a sectional view on the line 6—6, 45 of Fig. 1, through the brace;

Fig. 7 is a sectional view on the line 7—7, of Fig. 1; and

Fig. 8 is an enlarged fragmentary perspective of the upper end of the leg extension member and its brace connecting end.

Throughout the following detail descrip-

tion and on the several figures of the drawings, similar parts are referred to by like reference characters.

Referring to the drawings and specifically 55 describing the invention, 1 designates a top or board of suitable shape, depending, of course, upon the use to which it is to be put, that is whether designed for an ironing board, or a work bench, or the like. Beneath the board adjacent to each edge is disposed a clamping member 2 between which members and the extremity of the board 1 is adapted to be received the edge 3 of some support, such as a table, a stove, or similar object. 60

The clamping members are attached to the board 1 by the bolts 4 which extend through the respective members and through a transversely arranged spacing bar 5. The surface of this cross piece 5 is rounded so as to facilitate rocking of the clamping members upon this element. Each bolt carries a spring 6, seated against a bushing 6' for holding the spring in position, and has a winged nut 7 for adjusting the tension of 70

the spring which latter is adapted to yield as may be required in the clamping of the device to the sustaining support 3. In other words, this arrangement is particularly useful where the member 3 may be of different 75 thicknesses and by the provision of the yielding springs the jaws of the clamping means will readily adjust themselves accordingly.

To the inner ends of the clamping members is connected an operable supporting member or leg, designated 8, which member is provided with a longitudinally extending cut-out portion 9. In this cut-out portion is mounted an adjustable extension piece 10, by means of which the length of 90

the support may readily be controlled as may be required by the height of the main sustaining means 3 to which the board is attached. A sliding connection between the extension and the leg is afforded by providing the former with rounding or beveled edges which fit in the grooves of the leg, as clearly shown in Fig. 2 of the drawings, and in addition the extension is slotted longitudinally as indicated at 11, it being a closed 95 slot, so as to receive a clamping bolt 12. When the leg and its extension is adjusted

at the proper height, the clamping bolt 12 is tightened so as to hold the extension where desired, but I prefer not to depend upon this frictional adjustment where the board is subjected to heavy pressure, as when used as a work bench. To this end the leg is formed with a series of vertically arranged openings 13, while the upper end of the extension is slotted transversely, as shown in Fig. 8 5 at 14. A suitable pin 15, which is conveniently attached to the leg by a chain 16 is passed through the proper openings in the leg and into the groove 13 of the extension, insuring against movement of the extension 10 into the leg. It will be understood, of course, that the clamping bolt 12 is also utilized as above stated to prevent outward movement of the extension.

As clearly indicated in the drawings, the 20 leg 8 is pivotally connected adjacent to the upper end with the clamping members 2 by the pivot bolts 17 so that when the member 8 is swung about this pivot the extremity will contact with the under surface of the 25 board and act as a cam to move the clamping members on the cross piece 5 and thereby impart clamping action to the jaws.

The under surface of the board 1 is provided with stop or shoulder 18 which limits 30 the swinging movement of the member 8 in one direction and this member is held at the proper sustaining position by means of a brace 19 hingedly connected to the board near its outer end, as indicated at 20. This 35 brace is constructed quite like the leg 8, inasmuch as an extension slide 21 is mounted between the side pieces 20' and is clamped at adjusted position by means of the clamping bolt 22'. These side pieces 20' also have 40 openings 20" and at the end of the extension slide a groove to receive the pin 15 which may be inserted in this position in preference to insertion in the leg 8. The optional positions are shown in full and dotted lines, 45 respectively, in Fig. 1.

The special feature of the construction of the brace is the provision of pivot or end connection between the end of the brace extension slide 21 and the leg extension slide 50 10, at 22. The object of this arrangement is obvious for when the leg extension slide 10 is moved outwardly or inwardly to provide the proper adjustment, it carries with it the brace extension and thus a single adjustment only is required. The brace, of course, is designed to hold the upper end of leg against the shoulder 18, so that the board will not be accidentally collapsed in the event the leg is struck at either side in working around the board.

The use of the device hereinbefore described need not be further described, as these will be apparent to one skilled in the art to which the invention refers, unless it

is to say that its use may be extended to that 65 of acting as a saw clamp. When this is the case the saw is preferably placed between a couple of boards and then the boards and saw placed between the jaws of the apparatus hereinbefore described, that 70 is to say, the board and the clamping members, the leg being then operated to shift the clamping members so as to grip the saw tightly in position for working upon the teeth.

It may also be added that I prefer to provide as details of construction, a piece of asbestos at the under extremity of board 1, as indicated at 23, so as to prevent burning 80 of the wood when the board is attached to a stove. An aperture 24 may also be provided at each end of the board to enable it to be hung on a nail on the wall.

A work stop 25 may be mounted in the 85 board when it is desired to use the device as a work bench.

Figs. 3 and 4 show clearly the compact manner in which the board may be collapsed or folded as when it is desired to put the device away, or for shipping purposes. The 90 board may be locked in this folded position by passing the pin 15 through the proper openings 13 in the leg and through the transverse opening 26 in the upper part of the extension 10, as clearly shown in Fig. 8 of 95 the drawing.

Having thus described my invention, what I claim as new is:

1. An ironing board comprising means for attaching the same to a support consisting of a clamping member disposed beneath the board, a spacing bar on which the clamping member may be rocked, means operatively connected to one end of the clamping member for actuating the same to thereby impart clamping action against an object interposed between the other end of the member and the board, and yieldable pressure means holding the clamping member against the spacing bar and controlling the 110 pressure imparted by the operating means aforesaid.

2. An ironing board comprising means for attaching the same to a support consisting of the clamping member fulcrumed intermediate its length beneath the board and held spaced therefrom, a support for said ironing board connected to the clamping member and constituting a lever for imparting clamping action to said clamping member whereby to grip an object between the end thereof opposite the connection of the supporting member therewith and the ironing board, pressure means coacting with the clamping member and controlling the 115 clamping action on the object, and adjustable means on which said pressure means is mounted whereby to control the clamping 120 125

action imparted by the supporting member aforesaid.

3. A support of the class described comprising a top, a supporting leg therefor, 5 clamping means at one side operable by said leg for engagement with a support, brace means at the other side of said leg, and ex-

tension elements in said leg and brace means connected together for simultaneous adjustment whereby to position the support at 10 the proper height.

In testimony whereof I affix my signature.

DELPHIS BEAUPRE.
